UNITED STATES PATENT OFFICE.

WILLIAM P. SCHRAMM, OF NEW YORK, N. Y.

DESIGN FOR A COLLAR.

41,549.

Specification for Design.

Patented July 4, 1911.

Application filed December 31, 1910. Serial No. 600,365. Term of patent 7 years.

To all whom it may concern:

Be it known that I, WILLIAM P. SCHRAMM, a citizen of the United States, residing at 2854 Eighth avenue, borough of Manhattan, city, county, and State of New York, have invented a new, original, and ornamental Design for Collars, of which the following is a specification, reference being had to the accompanying drawings, forming part thereof.

The figure is a perspective view of a collar showing my design.

The design is for a close fitting wing col-

lar and is so constructed that the portion of which the wings form a part are parallel one to the other and are close together. In other respects the collar is not unlike many of the approved and well known forms of collars.

I claim:

The ornamental design for a close fitting wing collar as shown and described.
